Primary Examiner — Holly E Thurman*Assistant Examiner* — Bailey M Knotts(74) *Attorney, Agent, or Firm* — Kelley Drye & Warren LLP; Nathaniel Perkins; Alan D. Gardner(57) **CLAIM**

The ornamental design for a spotlight as shown and described.

DESCRIPTION

FIG. 1 is a front right perspective view of a spotlight in accordance with the present invention;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawing depict portions of the spotlight that form no part of the claimed design.
